SPRING ASSEMBLY FOR MATTRESSES

Eugene Joseph Hood, Carthage, Mo., assignor to Frank B. Williams and Harold E. Williams, Carthage, Mo.

Application March 24, 1948, Serial No. 16,758

8 Claims. (Cl. 5—351)

This invention relates to new and useful improvements in a spring assembly mattress and method for making the same, and has particular reference to a spring assembly providing a support for padding or upholstery to be carried by said assembly, whereby said padding or upholstery is prevented from working into the spaces within and between the component springs.

The principal purpose of this invention is the provision, in a spring assembly having a plurality of helical springs arranged in spaced apart parallel rows with the adjacent portions of the top and bottom loops of corresponding springs in each of said rows joined by a helical binder coil extending transversely to said spring rows, of a padding support carried on the upper surface of said assembly, said padding support comprising a plurality of wires extending over the surface of said assembly transversely of said binder coils and provided with transversely extending portions at said binder coils, said transversely extending wire portions extending through one or more of the convolutions of said binder coil, whereby said padding support wires are retained in substantially fixed relation relative to the spring assembly.

Other objects are simplicity and economy of construction, and ease of assembly.

With these objects in view, as well as other objects which will appear in the course of the specification, reference will be had to the drawing, wherein:

Figure 1 is a plan view of a spring assembly embodying the present invention.

Fig. 2 is a sectional view taken on line II—II of Fig. 1.

Fig. 3 is a fragmentary plan view of a spring assembly including a padding support of modified form.

Fig. 4 is a fragmentary plan view of a spring assembly showing a second modification of the padding support.

Fig. 5 is a fragmentary plan view of a spring assembly showing a third modification of the padding support.

Like reference characters apply to similar parts throughout the several views, and the numeral 10 applies to each of a plurality of helical springs, said springs being axially parallel and arranged in parallel spaced apart rows as shown in Fig. 1. Any number of springs may, of course, be used depending on the size of the spring assembly to be built. The top loops 12 and bottom loops 14 of said springs lie in substantially horizontal planes which will hereafter be designated respectively the upper and lower surfaces of the spring assembly. The top and bottom marginal edges of the spring assembly thus formed are bound by helical binder coils of relatively small diameter, binder coils 16 being coiled about the outer portions of the top and bottom loops of springs 10 at each end of the spring rows, and binder coils 18 being coiled about the outer portions of the top and bottom loops of springs 10 in each of the outer spring rows. The end loops of adjacent springs in each of the spring rows overlap slightly, and are joined together by binder coils 20, which extend in parallel relation transversely to the spring rows and join the overlapping portions of the end loops of corresponding springs in each of the rows. Each of

2

coils 16, 18 and 20 is securely anchored in place by having its end portions wrapped tightly about an adjacent loop of one of the helical springs 10.

The spring assembly thus far described is not new, and is disclosed only as a means for positioning and supporting the padding support hereinafter described. Said padding support comprises, in its preferred form as disclosed in Figs. 1 and 2, a plurality of wires 22 extending across the upper surface of the assembly transversely to the rows of springs 10. The greater portion of each of said wires is formed to present a plurality of spaced apart parallel reaches 24 parallel to the spring rows and extending between a pair of adjacent binder coils 20, or between a binder coil 20 and a marginal binder coil 16. Said parallel reaches are joined by transversely extending connecting portions 26, said connecting portions being disposed axially within one of the binder coils and extending through one or more full convolutions thereof. By thus positioning the connecting portions 26 of wires 22 within said binder coils, said wires are held securely relatively to the spring assembly. The end portions of wires 22 may be anchored by looping them around a convenient loop of one of the binder coils, and wrapping them around the top loop of one of springs 10. The distance between the parallel reaches 24 of the support wires is sufficiently small to be effective in preventing the padding of the mattress from working into the spaces within and between springs 10.

In the modified form shown in Fig. 3, the padding support is substantially similar to that of the preferred form, except that parallel reaches 28 of wires 30 each extend across two of the springs 10 of each row, the transversely extending portions 32 therefore being disposed in alternate binder coils 20. In the modification shown in Fig. 4, padding support wires 34 extend in substantially parallel relation across the spring assembly transversely to binder coils 20, each of said wires being oppositely offset at successive binder coils, and having the transversely offset portions 36 thereof disposed axially in said binder coils, whereby said wires are securely positioned. The end portions of said support wires are looped around convenient convolutions of marginal binder coils 16, as at 38. In the modification shown in Fig. 5, padding support wires 40 extend across the spring assembly transversely to binder coils 20 and generally parallel to the rows of springs 10, the end portions of said support wires being looped about convenient portions of marginal binder coils 16, as at 42. Each of said support wires is zig-zag in form, being transversely offset in the same direction at each of binder coils 20, and having said transverse offset portion 44 disposed axially in said binder coil.

What I claim is:

1. A spring assembly comprising a plurality of helical springs arranged in parallel rows with their top and bottom loops disposed respectively in parallel planes defining the upper and lower surfaces of said assembly, helical binder coils extending about the upper and lower marginal edges of said assembly and joining the outer portions of the top and bottom loops of the marginal springs, said top and bottom loops of adjacent springs in each row overlapping, a plurality of parallel helical binder coils lying in the plane of the upper surface of said assembly transversely to said spring rows and coiled about the overlapping portions of corresponding springs in each of said rows, and a plurality of sinuous wires extending across the upper surface of said assembly generally parallel to said parallel binder coils, each of said wires being formed to present a plurality of substantially parallel reaches transverse to said binder coils and extending across the distance of a plurality of springs in each of said spring rows, and transversely extending portions connecting said parallel reaches

and disposed longitudinally within the binder coils at each end of said parallel reaches.

2. A spring assembly comprising a plurality of helical springs arranged in parallel rows with their top and bottom loops disposed respectively in parallel planes defining the upper and lower surfaces of said assembly, helical binder coils extending about the upper and lower marginal edges of said assembly and joining the outer portions of the top and bottom loops of the marginal springs, said top and bottom loops of adjacent springs in each row overlapping, a plurality of parallel helical binder coils lying in the plane of the upper surface of said assembly transversely to said spring rows and coiled about the overlapping portions of corresponding springs in each of said rows, and a plurality of sinuous wires extending across the upper surface of said assembly generally parallel to said spring rows and transverse to said parallel binder coils, each of said wires having portions at intervals along its length disposed transversely to the general direction thereof, said transverse portions being disposed longitudinally within said binder coils.

3. A spring assembly comprising a plurality of helical springs arranged in parallel rows with their top and bottom loops disposed respectively in parallel planes defining the upper and lower surfaces of said assembly, helical binder coils extending about the upper and lower marginal edges of said assembly and joining the outer portions of the top and bottom loops of the marginal springs, said top and bottom loops of adjacent springs in each row overlapping, a plurality of parallel helical binder coils lying in the plane of the upper surface of said assembly transversely to said spring rows and coiled about the overlapping portions of corresponding springs in each of said rows, and a plurality of sinuous wires extending across the upper surface of said assembly generally parallel to said spring rows and transverse to said parallel binder coils, each of said wires having portions at intervals along its length, the transverse connecting portions of said wire at said offsets being disposed longitudinally within said parallel binder coils.

4. A spring assembly comprising a plurality of helical springs arranged in parallel rows with their top and bottom loops disposed respectively in parallel planes defining the upper and lower surfaces of said assembly, helical binder coils extending about the upper and lower marginal edges of said assembly and joining the outer portions of the top and bottom loops of the marginal springs, said top and bottom loops of adjacent springs in each row overlapping, a plurality of parallel helical binder coils lying in the plane of the upper surface of said assembly transversely to said spring rows and coiled about the overlapping portions of corresponding springs in each of said rows, and a plurality of sinuous wires extending across the upper surface of said assembly generally parallel to said spring rows and transverse to said parallel binder coils, each of said wires being substantially zig-zag in shape, alternate reaches of said wire being disposed generally parallel to said helical binder coils and being disposed longitudinally within said binder coils.

5. A spring assembly comprising a plurality of helical springs arranged with their top and bottom loops disposed respectively in parallel planes defining the upper and low-

er surfaces of said assembly, a plurality of helical binder coils lying in the plane of the upper surface of said assembly in parallel relation and coiled about the adjacent portions of the top loops of said springs to connect said springs, and a plurality of wires extending across the upper surface of said assembly, said wires having spaced apart parallel reaches transverse to said binder coils and having portions disposed axially within said binder coils.

6. A spring assembly comprising a plurality of helical springs arranged in parallel rows with their top and bottom loops disposed respectively in parallel planes defining the upper and lower surfaces of said assembly, helical binder coils joining the outer portions of the top and bottom loops of the marginal springs of said assembly, helical binder coils lying in the planes of the upper and lower surfaces of said assembly and coiling about adjacent portions of the top and bottom loops of corresponding pairs of springs in each of said rows, and a plurality of padding support wires extending across the upper surface of said assembly, said wires having spaced apart parallel reaches extending transversely to said last named upper binder coils and each having at intervals along its length portions parallel to said binder coils and disposed longitudinally within said upper binder coils, and extending through one or more convolutions thereof.

7. The combination, with a spring assembly of the class described having a plurality of helical springs arranged with their top and bottom loops disposed respectively in parallel planes defining the upper and lower surfaces of said assembly, said springs being joined by helical binder coils connecting adjacent portions of the top and bottom loops of said springs, of a plurality of generally parallel wires extending over the upper surface of said assembly transversely to said binder coils, and having portions disposed longitudinally within certain of said binder coils.

8. A spring assembly comprising a plurality of helical springs arranged in parallel rows with their top and bottom loops disposed respectively in parallel planes defining the upper and lower surfaces of said assembly, helical binder coils extending about the upper and lower marginal edges of said assembly and joining the outer portions of the top and bottom loops of the marginal springs, said top and bottom loops of adjacent springs in each row overlapping, a plurality of parallel helical binder coils lying in the plane of the upper surface of said assembly transversely to said spring rows and coiled about the overlapping portions of corresponding springs in each of said rows, and a plurality of sinuous wires extending across the upper surface of said assembly generally parallel to said parallel binder coils, each of said wires being formed to present a plurality of substantially parallel reaches transverse to said binder coils and extending between a pair of adjacent binder coils, and having portions connecting said parallel reaches and disposed longitudinally within said adjacent binder coils.
